UNITED STATES PATENT OFFICE.

OSCAR GASSETT, OF BOSTON, MASSACHUSETTS.

OIL-ENGINE.

No. 875,256.

Specification of Letters Patent.

Patented Dec. 31, 1907.

Application filed March 9 1903. Serial No. 146,890.

To all whom it may concern:

Be it known that I, OSCAR GASSETT, of Boston, county of Suffolk, and State of Massachusetts, have invented an Improvement in Oil-Engines, of which the following description, in connection with the accompanying drawings, is a specification, like letters on the drawings representing like parts.

10 The present invention relates to an internal combustion engine and is embodied in an engine capable of being operated with kerosene oil, the invention mainly relating to a certain novel construction and arrangement whereby the cylinder is thoroughly cleaned at the end of each working stroke and perfect combustion of the fuel obtained.

15 The invention further relates to novel means for vaporizing the fuel, the machine being provided with a vaporizer which projects into the cylinder, and is adapted to be heated in the first instance by means of a torch applied at the outside of the engine and afterwards by the heat of the combustion itself during the operation of the engine, the fuel inlet being so placed as to force a jet of oil against said vaporizer.

20 In accordance with the invention, the vaporizer projects into the inlet portion of the cylinder and is shown as in the form of a cup or shell open at its outer end whereby it may conveniently be subjected to the action of a suitable torch or other heating device, the oil being introduced to the cylinder so as to come in contact with the heated shell, which acts not only as a vaporizer but as a deflector for the oil which is thus at once vaporized and distributed throughout the volume of compressed air in the cylinder.

25 40 This vaporizing deflector, as it may be called, embodies an important feature of the invention, since it is due to this member that the oil introduced is at once vaporized and mixed with the air, so that no carbonizing of the oil takes place, and no fouling of the cylinder or

45 piston. The cylinder is supplied with compressed air in any suitable way, the piston during its out-stroke being herein shown as constituting a pump after the usual custom in two cycle engines, which compresses air and forces the same into the cylinder during the out-stroke of the piston, or rather as soon as the pressure behind the piston has become 50 reduced lower than that of the air compressed in front of the piston.

In accordance with the invention, the cylinder is further provided with means for supplying the charge with an agitating jet during the combustion thereof, said means being 55 herein shown as consisting of a supplemental chamber or pocket which receives air at a pressure equal to that of the air in the cylinder itself, the said pocket being herein shown as having a restricted passage in open communication with the cylinder, so that the air stored in said pocket escapes in a jet, so to speak, as the pressure within the cylinder becomes reduced, thus following the 60 burning oil and keeping the same thoroughly supplied with oxygen so as to obtain substantially perfect combustion, the action being somewhat similar to that of a blowpipe.

65 Figure 1 is a side elevation of an engine embodying the invention; Fig. 2 is a vertical longitudinal section of the same; Fig. 3 is a detail on a larger scale showing in section the oil pump; Fig. 4 is a sectional detail on the same scale as Fig. 3, showing the air inlet; 70 and Fig. 5 is a transverse section of the parts shown in Fig. 4, looking toward the right.

75 The engine embodying the invention is provided with the cylinder a containing the piston b , the said cylinder having at one end 80 an inlet-portion a^2 which is shown as smaller in diameter than the body of the cylinder, and at the opposite end a compression chamber a^3 , which is shown as containing the pitman connection b^2 , the construction thus far 85 being substantially the same as that in the ordinary type of two cycle engines, except for the difference in diameter between the inlet-portion and the body of the cylinder, which, however, is not essential to the present invention.

90 95 The piston is provided with an inner face b^3 and outer face b^4 , the latter having substantially twice the area of the former so as to act upon a large quantity of air in the chamber a^3 which is supplied with air through a pipe a^4 provided at one end with a check valve a^5 through which air is sucked into the chamber a^3 during the in-stroke of the piston. The said pipe a^4 is connected by 100 means of a pipe a^6 and suitable controlling valve a^7 , Fig. 4, with the combustion chamber a^2 , so that the compressed air in front of the piston will open the valve a^7 and blow into the explosion chamber as soon as the 105 working pressure therein is reduced by the opening of the exhaust ports a^8 which are

shown as in the side of the cylinder and controlled by the piston *b*.

The pipe *a*⁴ constitutes both the inlet and the outlet for the air, the check valve *a*⁵ being at the end of the pipe, there being, therefore, first a current of air in one direction and then a current of air in the opposite direction which tends to keep the pipe clear of foreign substances such as lubricating oil, and decreases the liability of accidental introduction of such substances into the cylinder.

The valve *a*⁷ will be maintained seated against the pressure of the compressed air during the working stroke when the pressure of the burning gases is greatly in excess of the compressed air pressure, but the said valve will open as soon as the exhaust ports are opened, letting a sudden rush of fresh air blow into the combustion chamber and cylinder, thus blowing out all the products of combustion through the exhaust ports, and thoroughly cleaning the cylinder. This action is only momentary, since the exhaust is almost immediately closed during the return movement of the piston and the compressed air is thus entrapped in the cylinder and further compressed by the return movement of the piston.

The fuel, such as kerosene oil, is introduced into the cylinder through a pipe *c* which opens at a point adjacent to the vaporizer *d*, said oil being forced in by means of a pump *e* which is provided with inlet and outlet check valves *e*² and *e*³ and a plunger *e*⁴ which is operated by a cam *e*⁵ on the main driving shaft *A*. As herein shown, the said cam acts upon one member of an elbow lever *e*⁶, the other member of which acts directly upon the end of the plunger rod *e*⁴ to cause the active stroke thereof, the return stroke being produced by means of a spring *e*⁶ which is introduced between a shoulder *e*⁹ upon the rod and an adjusting member *e*¹⁰.

The effective stroke of the pump is caused substantially at the time when the piston is at the end of its return stroke, a jet of oil thus being forced into the compressed air in the cylinder, the charge of combustible material thus formed being vaporized by means of the igniting cone *d*, which is shown as a comparatively thin shell projecting into the cylinder and primarily heated externally by means of the torch *d*² and kept heated by the heat of the combustion during the running of the engine, the compression being sufficient to cause the mixture of compressed air and vapor to burn.

The perfect combustion of the oil is assured in accordance with the present invention by agitating and oxidizing the charge during the combustion thereof. This may be accomplished by providing the cylinder with a supplemental chamber *f*, which is shown as in open communication with the inlet portion *a*² through a restricted passage

*f*², the said supplemental chamber receiving a quantity of pure air at a pressure equal to that of the air in the cylinder prior to the injection of the fuel, the said extra supply of air escaping into the cylinder as the pressure therein becomes reduced, thus blowing, as it were, an additional supply of oxygen into the burning fuel, as well as agitating and mixing the same to insure the complete combustion thereof.

To start the engine the vaporizer is heated, as previously stated, by means of a torch of any suitable kind, such for example as an ordinary gasoline torch, which may be removed as soon as the vaporizer is sufficiently heated to start the engine, for the reason that the heat of the combustion in the operation of the engine will maintain the said vaporizer sufficiently heated to vaporize the oil, or other fuel, when it is forced into the cylinder and supplied with air, the pressure being sufficient to cause ignition.

The supplemental chamber *f* with its supply of air which escapes at the proper time and is renewed by the incoming air through the pipe *a*⁴ when the exhaust is opened, gives an additional supply of oxygen which is distributed throughout the cylinder as the piston travels outward, the result being that substantially perfect combustion is obtained, so that the cylinder will not become fouled.

The speed and power of the engine may be perfectly controlled by simply controlling the amount of fuel introduced, this being accomplished in the construction shown by means of the adjusting member *e*¹⁰, which is shown as screw threaded in a portion of the supporting frame (see Fig. 3), and which forms an abutment or shoulder *e*¹² on the pump rod *e*⁴. The said pump rod is given a predetermined definite forward movement at each revolution by means of the cam *e*⁵, as hereinbefore described, the shoulder *e*¹² determining the initial position of the valve rod prior to the movement thereof. It is obvious, therefore, that if the adjusting member *e*¹⁰ is moved to the left, as through the agency of the screw thread, the initial or starting position of the pump rod will be nearer to the position to which it is moved through the agency of the cam, the result being that the pump has a shorter stroke and forces a smaller amount of fuel into the combustion chamber.

Claims.

1. In an internal combustion engine, a cylinder and piston; means for introducing compressed air to the cylinder, behind the piston, at the end of the outstroke thereof; means for introducing fuel to the cylinder; means for causing the operation of said introducing means substantially at the time when the piston has completed its stroke; a vaporizing deflector projecting into the cylinder behind the piston; and a supple-

mental chamber independent of the oil introducing means and of the vaporizing deflector, said chamber opening into the cylinder.

5. 2. In an internal combustion engine, a cylinder and piston; a vaporizer projecting into the cylinder behind the piston; means for introducing air into the cylinder; means for introducing fuel into the cylinder; and 10 a supplemental chamber opening into the cylinder, said chamber being independent of said vaporizer.

3. In an internal combustion engine, a cylinder and piston; a vaporizer projecting 15 into the cylinder behind the piston; a closed compressing chamber in front of the piston; an air pipe leading from said chamber to the rear end of the cylinder; inlet and outlet check valves near the cylinder ends of said 20 pipe; means for introducing fuel to the cylinder; a vaporizing deflector projecting into

the cylinder; and a supplemental chamber communicating with the cylinder, said supplemental chamber being independent of the 25 means for introducing the fuel and of the vaporizer.

4. In an internal combustion engine, the combination with the cylinder and piston; of means for introducing compressed air into the cylinder when the piston is substantially 30 at the end of its outstroke; an oil inlet; means for forcing oil into the cylinder through said inlet; and a supplemental independent chamber having a jet orifice communicating with the cylinder.

In testimony whereof, I have signed my name to this specification in the presence of two subscribing witnesses.

OSCAR GASSETT.
